SUGAR-CANE FEEDER

Allen M. Hewlett, Haina, Hamakua,
Territory of Hawaii

Application October 27, 1942, Serial No. 463,510

4 Claims. (Cl. 146—119)

The present invention relates to means for regulating the feed of sugar cane to the first mill and/or crusher in a cane sugar factory.

In one common form of apparatus for handling sugar cane, the cane is carried by a conveyor to the inlet upper end of an inclined chute and made to slide downwardly along the chute to the first mill and/or crushing rolls. It is important that the layer of sugar cane fed along the chute be maintained at a predetermined uniform thickness to assure efficient uniform operation of the first mill and/or crusher rolls.

One object of the present invention is to provide new and improved means for automatically regulating the feed of sugar cane to the first mill and/or crusher rolls to assure continuous delivery of a layer of uniform predetermined thickness to these units.

In my improved apparatus, the regulating means is in the form of a pivotally hanging gage plate near the inlet end of the chute adapted to scrape over and level off the feed blanket or layer as it slides downwardly along the chute. The angular movement of the gage plate about its pivot support resulting from variations in the thickness of the feed layer is transmitted to a device controlling the speed of the motor which drives the initial conveyor carrying the sugar cane to the inlet end of the chute. This device may, for instance, be the throttle valve of a steam or gas engine, or the rheostat controlling the speed of an electric motor, and is operated by the gage plate to slow down the conveyor when the thickness of the feed layer is increased beyond the desired predetermined value, and to speed up said conveyor when said thickness is reduced below said value.

The angular movement of said plate caused by variations in the thickness of the feed layer is not proportional to the variations in said thickness, and the motor speed control device is so automatically operated as to compensate for this variable relationship between the thickness of the feed layer and the angular movement of the gage plate.

Since the cane stalks delivered to the primary conveyor are usually in their field condition and therefore long, these would interfere with effective feed regulating operations of the gage plate. For that reason, there is provided as an additional feature a shredder, desirably in the form of a rotary cutter in advance of the gage plate.

As a feature of the present invention the gage plate serves not only as a means for regulating

the thickness of the cane feed layer, but also as a baffle to check the flying pieces of sugar cane propelled by the rapidly rotating shredder, and to hold the accumulated cane behind said plate and release it gradually and orderly as part of the levelled feed blanket as it emerges from below the plate.

Various other objects, features and advantages of the invention will be apparent from the following particular description, and from an inspection of the accompanying drawing, in which:

Fig. 1 is a side elevation somewhat schematic of my improved apparatus, certain parts being shown in vertical section;

Fig. 2 is a fragmentary perspective of a portion of the apparatus shown in Fig. 1;

Fig. 3 is a vertical section on an enlarged scale of the throttle valve for the conveyor motor;

Fig. 4 is a perspective of the rotary plug constituting part of the throttle valve for the conveyor motor.

Referring to the drawing, the sugar cane A 25 in its field condition is dumped on an inclined endless conveyor 10 in a trough 11, and transported obliquely upwardly thereby to a chute 12 for continuous delivery to a first mill and/or crusher rolls 13. The conveyor 10 is driven from any suitable type of motor which, for the purpose of illustration, is shown as a steam engine 14, but which may also be a gas or electric motor. The speed of this motor 14 is regulated by a control device 16, which in the case of a 35 steam engine would be a throttle valve in the steam line 17 of said engine.

The chute 12 slopes downwardly away from the conveyor 10, and having its upper inlet end adjacent to the discharge end of said conveyor, 40 and its lower end adjacent to the first mill, and/or crusher rolls 13. The chute 12 should be sufficiently long and be inclined at a sufficiently steep angle to permit free gravitational flow of sugar cane therealong. For that purpose, it should slope at an angle of about 45°.

A cane shredder 20, shown as a series of radial knives is employed at the upper end of the trough 11 near the discharge end of the conveyor 10, and is driven at high speed from any suitable source 50 of power to subdivide the cane A just prior to its discharge into the chute 12. This cane shredder 20 may, for example, comprise sixteen knives arranged along the supporting shaft and driven at a constant speed ranging from 400 to 600

To automatically regulate the thickness of the shredded cane layer B sliding along the chute 12 towards the crusher rolls 13 and to prevent the shredded cane from being thrown out by the shredder, there is provided a downwardly hanging pivotally supported gage plate 21 extending substantially across the entire cross-sectional area of said chute, and having its free lower end adapted to bear on the surface of said layer. The pivotal support for this gage plate 21 includes a rock shaft 22 journaled in bearings 23 in the side walls of the chute 12, and rigidly secured to said plate by suitable fastening means such as lugs 24. One end of this shaft 22 projects beyond the side of the chute 12, and is connected to the throttle valve 16 through a transmission mechanism so that said valve is opened or closed to an extent determined by the angular movement of the gage plate 21. This transmission mechanism is shown including an arm 26 affixed to the projecting end of the shaft 22 and pivotally connected to one end of the link 27, the other end being pivotally secured to an arm 28 rigid with the operating member of the valve.

The steam valve 16 is desirably of the rotary type having a valve plug 30 fitted for rotation in the valve casing or plug cock 31, and having a valve passage 32. A head 33 at one end of the valve plug 30 has a turning engagement with the arm 28.

To permit adjustments in the linkage described, the link 27 desirably includes a turn-buckle 34, and the arms 26 and 28 have a series of spaced holes by which their effective lengths can be altered.

As the shredded cane is discharged into the chute 12, it collects behind the gage plate 21, and then flows below the lower edge of said plate downwardly along the inclined floor of the chute 12. As this cane passes under the gage plate 21, it is levelled off by said plate. The gage plate 21 is urged against the cane layer B with substantial pressure so that occasional stalks projecting upwardly from the mean surface level of the feed layer are pressed downwardly on said surface to avoid disturbing the effective operation of the plate. For that purpose a weight 36 is suspended from the outer free end of the arm 26.

As the gage plate 21 is angularly moved from the position shown in full lines towards the position indicated in dot and dash lines by an increase in the thickness of the feed layer B, the valve plug 30 is rotated by the linkage 26, 27 and 28 to permit less steam to flow to the steam engine 14, so that said engine is slowed down, the conveyor 10 is reduced in speed and the rate of discharge into the chute correspondingly reduced.

Since the gage plate 21 extends almost vertically downwardly with a shallow feed layer, successive equal increases in the thickness of said layer cause progressively smaller changes in the angular position of said gage plate as said plate approaches the dot and dash line position shown. To offset this varying ratio between the two movements involved, so that the flow of steam to the engine 14 is varied inversely as the thickness of the feed layer, the steam pipe 11 and the plug cock 31 are oversized, and the valve passage 32 in the plug 30 has a valve opening which changes at a varying rate for equal successive increments of rotation of said plug. For that purpose, a pair of similar triangular plates 40 are welded to the plug 30 in the valve passage 32 to form a substantially triangular orifice 41, and said plug is so positioned in its casing 31 that

the apex 42 of said orifice leads when said plug is being rotated in closed position. The variation in orifice area exposed to open position per increment of change in the thickness of the feed layer will always be substantially the same in any part of the operating range of the gage plate 21. As far as certain aspects of the invention are concerned, the orifice 41 may be shaped in any other way according to the characteristics of the machine and the displacement characteristics of the transmission mechanism between the gage plate 21 and the valve 16.

The desired variation between the angular movement of the gage plate 21 and the extent of operation of the valve 16 can be effected by other means. For instance, the linkage may be constructed to give different angular movements of the valve 16 for equal increments of angular movement of the plate 21 in different parts of its operating range, or if desired, a properly designed cam or eccentric may be mounted in the transmission between said plate and said valve. Such a cam, for instance, could be positioned on the projecting end of the shaft 22 and the arm 26 may be pivotally supported at a point spaced from said shaft and may have a follower engagement with said cam.

In case an electric motor is employed to drive the conveyor 10, a suitable rheostat in the circuit 30 of said motor can be made to serve as the speed control means for said motor, and can be operated from the gage plate 21 through a variable displacement linkage, a cam or an eccentric as described, or can be operated from the linkage 35 as shown, providing the rheostat coils are variably wound, so that the extent of resistance cut in progressively varies for successively equal increments of slider travel. Considerable torque is exerted through the shaft 22, so that ample power 40 is afforded to operate a rheostat as described.

The gage plate 21 extending across the full width of the chute and up to the top of the chute 12 serves as a baffle to check the flying pieces of sugar cane propelled by the rapidly 45 rotating shredder 20, and to hold the accumulated cane behind said plate and prevent it from rolling helter-skelter down the chute.

A stop 43 limiting backward movement of the plate 21 prevents complete closure of the space between the lower edge of said plate and the chute floor and jamming of said plate in closed position.

To permit manual regulation of the speed of the conveyor 10, there is provided a hand valve 44 in the steam line 17, and a by-pass steam line 45 with 55 a hand valve 46. This arrangement permits the speed of the engine 14 to be manually controlled through manipulation of the valve 46, when valve 44 is closed.

As many changes can be made in the above 60 apparatus, and many apparently widely different embodiments of this invention can be made without departing from the scope of the claims, it is intended that all matter contained in the above 65 description or shown in the accompanying drawings shall be interpreted as illustrative and not in a limiting sense.

What is claimed is:

1. A combined sugar cane shredder and feeder comprising an inclined chute, a conveyor for discharging sugar cane to said chute, a motor for driving said conveyor, a cane shredder near the discharge end of said conveyor for subdividing the cane prior to its discharge onto said chute, a gage member against which the shredded cane is discharged by said shredder, said gage member yield-

ably bearing on the layer of cane in said chute and movable by variations in the thickness of said layer passing under said member, and means automatically operable by the movement of said member for varying the speed of said motor substantially inversely to the thickness of said layer.

2. In a sugar cane feeder, the combination comprising an inclined chute, a conveyor for discharging sugar cane to said chute, a motor for driving said conveyor, a depending pivotally supported gage plate having its lower free end yieldably bearing on the layer of sugar cane in said chute, whereby said plate is angularly moved according to the thickness of said layer, a high speed rotary shredder in advance of said gage plate for subdividing the cane prior to its delivery below said gage plate, and means automatically operable by the angular movement of said plate for varying the speed of said motor substantially inversely to the thickness of said layer, said plate being sufficiently close to said shredder to check flying pieces of cane propelled by said shredder.

3. In a sugar cane feeder, the combination comprising an inclined chute, a conveyor for discharging sugar cane onto the upper inlet end of said chute, a shredder adjacent to the discharge end of said conveyor, a motor for driving said conveyor, a gage plate in said chute extending substantially across the entire width of said chute and across a substantial part of its height and having a pivotal support at an elevation which will permit said plate to hang down almost vertically when said chute is free of sugar cane, the

free lower end of said plate being adapted to bear on the layer of cane in said chute, whereby said plate is angularly moved according to the thickness of said layer, said plate being sufficiently close to said shredder to check flying pieces of cane propelled by said shredder, and means automatically operable by the angular movement of said plate for varying the speed of said motor substantially inversely to the thickness of said layer.

4. In a sugar cane crusher feeder, the combination comprising an inclined chute, a conveyor inclined upwardly towards the upper inlet end of said chute, a rotary shredder for discharging sugar cane from said conveyor to said chute, a motor for driving said device, a device for controlling flow of actuating power to said motor, a gage plate in said chute extending substantially across the entire width of said chute and across a substantial part of its height, and having a pivotal support at an elevation which will permit said plate to hang almost vertically downwardly when said chute is free of sugar cane, whereby said plate acts as a baffle for the cane discharged by said shredder into said chute, the free lower end of said plate being adapted to bear on the layer of cane in said chute, whereby said plate is angularly moved according to the thickness of said layer, and means for transmitting the angular movement of said plate to said device to vary the speed of said motor substantially inversely to the thickness of said layer.
